APPARATUS FOR CONTINUOUS HEATING
AND COOLING OF METALSKristian A. Juthe, Newton Center, Mass., assignor
to American Electric Furnace Company, Dor-
chester, Mass., a corporation of Massachusetts

Application July 9, 1938, Serial No. 218,409

6 Claims. (Cl. 266—5)

This invention relates to a new apparatus for continuously heating and cooling ferrous and non-ferrous metals under controlled atmospheric conditions.

5 It is designed especially for efficient continuous bright or clean annealing on a production basis of relatively small pieces of work of copper, brass, steel or the like.

In practicing my invention I assemble a furnace 10 unit and a cooling unit in end-to-end relationship, and provide both units with automatic direct-connected work feeding devices whereby the work is automatically and continuously fed through the furnace and cooling units. During 15 the passage of the work through said units it is subjected to an artificially produced neutral or gaseous atmosphere which is maintained within close limits of control at all times in both units, and especially at the charging end of the furnace 20 retort and the discharge end of the cooling unit. As a result, the work is not only continuously and rapidly fed through both units but is treated under such closely controlled atmospheric conditions as to eliminate any tendency of the surface of 25 the work to scale, decarburize, or oxidize.

Heretofore the conventional method for cooling the work after it left the heating chamber of the furnace was to pass it through an extended cooling chamber equipped with an endless conveyor, 30 such as a belt or a roller conveyor.

One objection to the conventional method was the floor space required for setting up the cooling chamber and the shipping space required for shipping the cooling chamber from point of manu- 35 facture to point of use.

Due to the character of the conveyor employed in the cooling chamber, the cooling chamber necessarily had to be of considerable length in order to provide adequate cooling time for the 40 work, being usually approximately three times as long as the furnace chamber.

In addition to this objection, another objection was that proper atmospheric control could not be maintained at all times and in all areas of the 45 furnace chamber and cooling chamber. This was due to a number of factors, chief among which was the difficulty of relating the feed of the work through the furnace chamber to the feed of the work through the extended cooling chamber with- 50 out undue loss of the neutral or gaseous atmosphere as the work discharged from the furnace chamber into the cooling chamber and as the work discharged from the cooling chamber.

My present invention avoids these objections. 55 According to it, the furnace unit is provided with

a rotatable retort having an integral internal spiral screw conveyor. This retort extends from end to end of the furnace chamber and through both ends of the furnace, being supported at its ends on anti-friction bearings. 5

At its charging end the retort is provided with a loading drum having an internal loading device for automatically loading the work into the retort and at the same time for retarding the escape of atmosphere from the retort. 10

At its discharge end, the retort is fastened directly to an enlarged cooling drum having an internal spiral screw conveyor. The cooling drum is likewise rotatably supported on anti-friction bearings, and being directly connected to the retort, continuously rotates in unison therewith. 15

The discharge end of the cooling drum is provided with a work discharge chute equipped with a normally closed shutter which automatically opens preferably once each revolution of the cooling drum to discharge the finished work and instantly closes to prevent the escape of the neutral or gaseous atmosphere therefrom. The opening and closing of the discharge shutter is positive and automatic, being controlled by a cam or equivalent device. 20

The cooling drum itself is continuously cooled with water or other cooling fluid by spray nozzles disposed exteriorly thereof. The water discharged from said nozzles cools the drum as it 30 revolves and drains into a tank beneath the drum, the level of the water in such tank being so adjusted that the drum is partially submerged in it as it rotates therethrough.

The retort and cooling drum are driven as a 35 unit from any suitable power source, as for example, a motor operated variable speed drive and reduction unit, the discharge end of the retort being flanged and directly attached to the intake end of the cooling drum and the drive sprocket 40 being also bolted to the retort flange preferably by the same bolts which couple these ends of the retort and cooling drum together.

The necessary artificial atmosphere required during heating and cooling of the work to prevent discoloration, scaling, decarburization or oxidation of the surface of the work and to ensure bright or clean annealing, is supplied from a separate atmospheric unit. This unit discharges axially into the cooling drum at the work 50 discharge end of said drum, the atmosphere thus supplied passing through the drum and through the charging chamber of the furnace and filling both chambers so that at all times and in all areas of both chambers the work in its passage 55

through said chambers is exposed to a substantially constant and substantially uniform neutral or gaseous atmosphere. The action is in the nature of a regenerative action in that the work and gases are moving in opposite directions, the cold gas entering at the work discharge end of the cooling drum being heated by the hot work passing through said drum and as these heated gases pass over the work in the charging chamber of the furnace some of their heat is transmitted to the work, particularly in the region of the charging end of the furnace chamber.

If desired, a portion of the gas may be bypassed to the work discharge chute to fill such chute and prevent outside atmosphere from entering the chute when its discharge shutter is momentarily opened for the discharge of the finished work. The pressure of the gas within such chute is positive and is slightly higher than that of the outside atmosphere, thereby affording a gaseous seal at this point.

In the accompanying drawings I have illustrated one embodiment of my invention which I have found highly satisfactory under conditions of actual commercial use.

In such drawings:

Fig. 1 is a top plan view of my apparatus.

Fig. 2 is a longitudinal section on the line 30 2-2, of Fig. 1.

Fig. 3 is a front elevation of Fig. 1.

Fig. 4 is a vertical section on the line 4-4, of Fig. 2.

Fig. 5 is a rear elevation of the cooling drum assembly.

Fig. 6 is an enlarged fragmentary longitudinal section particularly showing the method of directly connecting the flanged discharge end of the rotating retort to the intake end of the cooling drum and the mounting of the drive sprocket on said flanged discharge end.

Fig. 7 is a fragmentary sectional detail on the line 7-7, of Fig. 5, particularly showing the cam plate and associated parts for automatically opening the shutter in the discharge chute at the work discharge end of the cooling drum.

Fig. 8 is a side elevation, partly broken away, at the work discharge end of the cooling drum, and

50 Figs. 9, 10 and 11 are fragmentary details further illustrating the quick acting shutter of the discharge chute and the mechanism for automatically opening and closing the same.

I have indicated generally at 1 a furnace unit and at 2 an axially aligned cooling unit. Both units are suitably supported on frames F and F' each unit being a complete assembly in itself.

The furnace unit includes a rugged shell 3 made of steel plate or the like. The heating chamber 4 is lined with any suitable high refractory 5 which is backed up with any suitable insulation 6. This chamber may be heated in any suitable manner as by electricity, gas, etc. As shown it is heated by electricity, conventional heating elements being indicated at 7 in Fig. 2. If desired, the heating elements may be divided into separate zones (see Fig. 1) to assist in maintaining positive uniformity throughout the furnace chamber and any suitable automatic temperature control may be provided.

Extending from end to end of the heating chamber and through both ends of the furnace unit is a rotatable retort 8 which is direct-connected at its discharge end with the adjacent 75 end of the cooling unit so that the retort and

cooling unit rotate in unison. The retort 8 is supported at its ends on suitable trunnions 9 rolling on taper roller bearings 10 mounted in any suitable supports 11 carried by the frame F. The trunnion race at the discharge end of 5 the retort is constructed as a pair of spaced annular flanges 9' (see Figs. 2 and 6) within which the roller bearings 10 at this end of the retort closely track, and these flanges in conjunction with said roller bearings have the further function of preventing end play of the retort and cooling drum during operation of the apparatus.

Integral with the retort and extending from end to end thereof is an internal spiral screw 15 conveyor 12. Attached to the charging end of the retort is a loading drum 13 having a work intake opening 14. The work is continuously fed into the intake end of said drum by means of any suitable inclined trough or the like (not 20 shown) and is picked up by the loading drum at each revolution thereof and fed through a pair of aligned charging slots 15 in the drum and retort, respectively, by means of a pair of oppositely disposed charging scoops 16 internally 25 of the loading drum. Each scoop 16 is shaped to deliver the work picked up within the drum to the registering charging slots 15 at each half revolution of the drum and retort, so as to ensure a continuous feed of the work to the spiral 30 screw conveyor 12 of the retort. If desired, means, such as adjustment screws, may be provided on the rear face of the drum for changing the dimension of the charging slots 15.

The conveyor 12 progresses the work continuously through the retort and into the adjacent end of the cooling unit 2. This unit consists of a drum, preferably of greater diameter than the diameter of the retort and direct-connected thereto.

Fast to the cooling drum internally thereof is an internal spiral screw conveyor 17 in axial prolongation of the screw conveyor 12 of the retort.

The cooling drum is rotatably supported at its work discharge end by means of a trunnion 18 running on roller bearings 19 similar to the trunnion and roller bearing support of the retort.

At its work intake end the cooling drum is 50 direct-connected to the discharge end of the retort, preferably by means of an annular flange 20 at the discharge end of the retort which is bolted or otherwise fastened as at 21 to the adjacent apertured end plate 22 of the cooling drum (see Fig. 6).

The retort and cooling drum are driven as a unit from any suitable drive source. As shown, the drive is from a motor M through a variable speed drive 23 and reduction unit 23' (Fig. 4), the driving sprocket of the reduction unit being 60 connected by a roller chain 24 to a driven sprocket 25 on the retort. Preferably the sprocket 25 is bolted to the retort flange 20 by the same bolts 21 which bolt said flange to the end plate 22 of the cooling drum.

Additionally, the cooling drum assembly may be bolted to the furnace unit assembly by means of the rails R (see Fig. 1).

The cooling drum is continuously water cooled 70 by means of spray pipes 26 and 27 suitably supported exteriorly of the drum at any desired locations. The water from these pipes washes the drum as it revolves therewith and drains into a tank 28 beneath the drum. The water in this 75

tank is maintained at a level sufficient that the drum is partially immersed as it rotates there-through.

At the discharge end of the cooling drum I 5 bolt or otherwise attach as at 29' (Fig. 5) a work discharge chute 29 which rotates with the drum and is fitted at its discharge end with a quick opening and closing shutter 30 which is timed to the rotation of the drum and preferably opens 10 once each revolution of the drum to discharge the finished work and instantly closes.

The inner end of the discharge chute projects through registering discharge slots 31 (see Fig. 8) in the adjacent end plate of the cooling drum 15 and its trunnion 18, respectively, and in conjunction with the final turn of the spiral screw conveyor 17 forms a pocket 32 constituting the intake end of the discharge chute.

Just prior to the moment that the discharge 20 chute in its rotation with the cooling drum reaches the down position shown in Figs. 5 and 8, the work discharge shutter 30 is automatically opened to discharge the finished work and instantly closed.

25 The mechanism for accomplishing the quick opening and closing of said shutter in time with the rotation of the cooling drum is detailed in Figs. 7 to 11, inclusive. Referring to these figures it will be noted that the shutter is spring-controlled and cam actuated and opens and closes by a right line sliding movement across the lower end of the discharge chute.

30 Adjustably mounted in any suitable manner on the supporting frame F' for the cooling drum 35 is a stationary cam plate 33 (see Fig. 7) having equidistantly spaced cam surfaces 34 and 35. The leading cam surface 34 is a shutter-opening surface and the following cam surface 35 is a shutter-return surface. These cam surfaces lie 40 at either side of the center line of the plate which is also the center line of the discharge chute.

The leading cam surface 34 is adapted to be contacted once each revolution of the cooling drum and discharge chute by a cam follower 36 45 mounted on the short arm 37 of a crank lever 37-38. The crank lever is pivoted at 39 to any suitable supporting bracket 40 carried by the chute. The long arm 38 of the crank lever is 50 adjustably connected in any suitable manner to the quick acting shutter 30. As shown this arm is provided with an elongated slot 41 receiving a roller 42 projecting from a cross bar 43 fixed to the outer surface of the shutter 30.

55 The marginal edges of the shutter are guided in a slideway 44 fastened to the underside of the discharge chute and this slideway is preferably laterally extended as at 45 (see Figs. 10 and 11) to constitute a support for the shutter when opened.

60 The return movement of the shutter occurs when the cam follower 36 passes the center line of the cam plate 33 and onto the return cam surface 35 of said plate. During this travel the crank lever 37-38 is moving against the tension 65 of a shutter closing spring 46, one end of which is anchored as at 47 to the discharge chute 29 and the other end of which is anchored as at 48 to a bell crank 49 pivoted as at 50 to the slideway for the shutter 30.

70 Pinned to the edge of the bell crank 49 remote from the edge at which the spring 46 is anchored is one end of a link 51. The other end of said link is formed as an eye adapted to be assembled with an eye-bolt 52 fixed to the long arm 38 of the crank lever 37-38. When the cam follower

36 passes off the return surface 35 of the stationary cam plate 33, the tension on the spring 46 is relieved and said spring closes the shutter by sliding it in reverse direction to its opening motion.

In order to assist in preventing escape of the gaseous or neutral atmosphere from the discharge chute during the opening movement of said shutter, I may pivot interiorly of the discharge chute an inclined sealing flap or clapper 10 54. Normally, this flap closes the discharge opening of the chute, the free edge of said flap being preferably upturned as at 55 and resting upon the inner surface of the shutter 30 when said shutter is closed (see Fig. 11). So positioned, 15 it relieves the shutter 30 of the weight of the finished work in the discharge chute as the discharge chute rotates towards its discharge position. When the shutter is opened the weight of the work resting on the flap 54 automatically 20 swings said flap about its pivot 53 into the dotted line position of Fig. 11. In its return motion, the adjacent edge of the shutter strikes the upturned edge 55 of said flap 54 and pushes the flap back to its full line position of Fig. 11 within 25 the discharge chute.

Any suitable artificial atmosphere as a gaseous or neutral atmosphere may be continuously supplied to and maintained within the cooling drum and furnace unit. Where a gaseous atmosphere 30 is supplied it may be introduced under pressure at the work discharge end of the cooling drum in counter flow relation to the direction of feed of the work from any suitable gas cracking unit, 35 not shown.

Referring to Fig. 8 I have indicated at 56 a supply connection for the artificial atmosphere. The supply 56 has an elbow connection at 57 with an axial pipe 58 which rotates with the cooling drum, being supported and braced by 40 means of any suitable support 59 attached to the adjacent end of the cooling drum. The axial pipe 58 has an offset discharge pipe 60 entering the cooling drum. The axial pipe 58 is journaled at one end in a bearing 61 on the cooling drum 45 and at its other end rotates in a swivel joint 62.

If desired a portion of the artificial atmosphere may be by-passed to the discharge chute 29 by means of the by-pass connection 63. The atmosphere thus by-passed into the discharge 50 chute 29 acts as a pressure seal to assist in preventing loss of the atmosphere through the work discharge end of the tube 29 when the shutter 30 is opened by excluding the entrance of outside air into the discharge chute.

The artificial atmosphere is continuously circulated over the work contained in said drum and in the retort, filling the drum and retort. The action is in the nature of a regenerative action in that the gas discharging into the cool end 60 of the cooling chamber absorbs some of the heat of the work in said chamber and as it passes toward the heating chamber of the furnace delivers its heat to the work within said heating chamber, thereby augmenting to some extent the heating 65 action. The gas vents at the charging end of the furnace. The design of the loading drum, however, is such that undue loss of the artificial atmosphere is prevented. Thus during its progress from end to end of the apparatus, the work 70 is continuously subjected to the protective action of the gaseous atmosphere. This action is constant at all times and in all areas of the apparatus. The work is also subjected to a sustained burnishing action, being turned over and over 75

upon itself by the spiral screw conveyors of the furnace and cooling units.

5 Due to the circumstance that the internal spiral screw conveyor of the cooling drum spreads the work out toward the water-cooled wall of the cooling drum in a relatively thin layer or layers substantially uniform cooling of the work is made possible.

10 Although I have shown a work charging and discharging arrangement in which two charges of work are placed in the intake end of the screw conveyor 12 at each complete revolution of said conveyor and a single charge is discharged at each complete revolution of the cooling drum, 15 such arrangement is optional and may be changed as desired.

20 The temperature of the work discharged will vary with the temperature of the retort, the volume and temperature of the cooling water, and the speed of rotation of the drum. These are all variable factors which may be regulated at will.

25 Various other modifications in machine and method may obviously be made, depending upon the nature of the work being treated and the wanted characteristics in the finished work.

What I therefore claim and desire to secure by Letters Patent is:

30 1. Apparatus for continuously heating and cooling ferrous and non-ferrous metals, comprising a furnace having a heating chamber, means for heating said chamber, a retort rotatably mounted within said chamber and extending from end to end thereof, a spiral screw conveyor fast to said retort internally thereof, a cooling drum rotatably mounted at the discharge end of said retort and direct-connected thereto to rotate in unison therewith, a spiral screw conveyor fast to said drum internally thereof and disposed in 35 axial prolongation of said first-named conveyor, means for cooling said drum, means for imparting continuous rotation to said retort and drum, a discharge chute fast to the discharge end of said cooling drum to rotate therewith, a shutter 40 at the discharge end of said chute, and means for automatically opening and closing said shutter in timed relation to the rotation of said drum.

45 2. In combination, a furnace having a heating chamber, a retort rotatable in said chamber, work feed means internally of said retort and rotating therewith, a cooling drum aligned with said retort and direct-connected thereto to rotate in unison therewith, work feed means internally of said drum and rotating therewith for progressing the work fed thereto from said retort to the discharge end of said drum, a work discharge chute at the discharge end of said cooling drum and rotating therewith, and having an automatically opening and closing work discharge shutter, a supply pipe rotatably mounted on the discharge end of said drum and having an inlet leading into said drum for introducing

5 artificial atmosphere under pressure into said drum in counter-flow to the direction of the feed of the work, and a by-pass from said supply pipe delivering to said discharge chute adjacent the shutter thereof.

10 3. In combination, a furnace having a rotatable retort, a cooling drum aligned with and direct-connected to said retort to rotate in unison therewith, means for continuously feeding work through said retort and drum, a work discharge chute rotating with said drum at the discharge end thereof, an automatic shutter at the discharge end of said chute, and means timed to the rotation of said drum for automatically opening and closing said shutter.

15 4. The combination of claim 3, and an inclined flap pivoted interiorly of the chute above the shutter with its free edge resting on the shutter to open automatically with the pressure of the work when the shutter is opened and to be restored automatically to normal position by the shutter when the shutter is closed.

20 5. The combination of claim 3, the means for automatically opening and closing said shutter comprising a stationary cam plate having spaced 25 shutter opening and closing cam surfaces, a pivoted crank lever having one arm connected to said shutter and another arm provided with a cam roll for initial coaction with the shutter-opening cam surface of said plate to open said 30 shutter and for subsequent coaction with the shutter closing cam surface of said plate to close said shutter, a bell crank pivoted adjacent said shutter, a spring connected at one end to said chute and at its opposite end to said bell crank, 35 and a link fastened at one end to said bell crank and at its other end to the second-named arm of said crank lever to close said shutter when the cam roll in its continued movement over said cam plate reaches the shutter closing cam 40 surface of said cam plate.

25 6. In combination, a furnace having a furnace chamber, a retort rotatable in said chamber, work feed means internally of said retort and rotating therewith, a cooling drum aligned with 45 said retort and direct-connected thereto to rotate in unison therewith, a spiral screw conveyor fast to said drum internally thereof and rotating therewith for progressing the work fed thereto from said retort to the discharge end of said 50 drum, a work discharge chute at the discharge end of said drum and rotating therewith, said chute having its inner end extending into the drum and in conjunction with the final turn of said spiral screw conveyor forming a pocket for directing the treated work into said chute, an automatically opening and closing work discharge shutter at the discharge end of said chute, and means for positively opening and closing said shutter in timed relation to the rotation of said 55 drum.

KRISTIAN A. JUTHE.
